UNITED STATES PATENT OFFICE.

HEMAN P. BROOKS, OF BROOKLYN, NEW YORK, ASSIGNOR TO HIMSELF
AND JAMES L. CARSON, OF TORRINGTON, CONNECTICUT.

BOTTLE-STOPPER.

SPECIFICATION forming part of Letters Patent No. 319,554, dated June 9, 1885.

Application filed March 2, 1885. (No model.)

To all whom it may concern:

Be it known that I, HEMAN P. BROOKS, of Brooklyn, in the county of Kings and State of New York, have invented an Improvement 5 in Bottle-Stopper Fastenings, of which the following is a specification.

Bottle-stoppers have been made in which an elastic stopper is connected to a metallic button, and the latter is provided with a bail and 10 a pivoted lever, by means of which the stopper is pressed upon the mouth of the bottle.

In my improvement the stopper-bail is provided with longitudinal slots through which pass the ends of the neck-band wire, and these 15 ends of the neck-band wire also form pivots upon which the stopper-bail can be swung to press the stopper upon the neck of the bottle, or away from the same, and a wire lever with double cams is pivoted to the said neck-band 20 wire and acts against the lower ends or feet of the bail to force the same down and press the stopper upon the neck of the bottle.

In the drawings, Figure 1 is a side elevation of the upper end of a bottle with the stopper 25 pressed close upon the same. Fig. 2 is a similar view with the stopper opened, and Fig. 3 is an elevation at right angles to Fig. 1.

The bottle A is provided with the ordinary mouth at the upper end of the neck, and 30 around the same is a neck-band, b, having projecting pivots c at the end, and D is a wire loop for securing the neck-band to the bottle, as usual. The stopper is composed of india-rubber E upon a button or base, F, and G is 35 a bail extending across and attached to the

stopper and provided with vertical slots extending along the lower portions of the bail, and at K are feet extending out laterally from the lower ends of the bail G.

There is a lever, L, having two arms, l, with 40 eyes at their ends through which the neck-band pivots c project, and the portions N of the lever L are cam-shaped, so that as the said lever L is swung down upon the pivots c the cam portions N will act upon the feet at the 45 lower ends of the bail G and press the stopper firmly into its place.

When the lever L is thrown up into the position shown by dotted lines in Fig. 1, the parts are liberated and the bottle-stopper can be 50 opened. When it is thrown back the other way the stopper is closed and forced firmly to the neck of the bottle.

I claim as my invention—

The combination, with the rubber stopper 55 E and button F, of the bail G, slotted longitudinally near the lower ends thereof, the neck-band b, having projecting ends passing through slots in the bail G, a lever with two arms pivoted at their ends to the ends of the neck-band 60 wire, and the feet K projecting at the lower ends of the bail, against which the cam portions N of the lever L act, substantially as set forth.

Signed by me this 17th day of February, A. 65 D. 1885.

HEMAN P. BROOKS.
